(57) **CLAIM**

The ornamental design for a shelf bracket, as shown and described.

DESCRIPTION

FIG. 1 is a left front perspective view of a shelf bracket according to my novel design;

FIG. 2 is a front elevation view, thereof, the rear elevation view thereof being a mirror image; the cut-away portions of the cabinet wall and a shelf shown in broken lines included solely for illustrative purposes, forming no part of the claimed design;

FIG. 3 is a top plan view, thereof;

FIG. 4 is a left side elevation view, thereof;

FIG. 5 is a bottom plan view, thereof;

FIG. 6 is a right side elevation view, thereof; and,

FIG. 7 is a reduced scale perspective view, showing the article in environment; the cabinet walls and shelf shown in broken lines included solely for illustrative purposes, forming no part of the claimed design; the broken line representation of the opposing shelf bracket included solely for illustrative purposes.
